1,461,692

UNITED STATES PATENT OFFICE.

ANDREW YUROW, OF NEW YORK, N. Y., ASSIGNOR TO SAMUEL M. ELOWSKY, OF BROOKLYN, NEW YORK.

LOCK.

Application filed August 2, 1922. Serial No. 579,247.

To all whom it may concern:

Be it known that I, ANDREW YUROW, a citizen of the United States, and a resident of the city of New York, borough of Manhattan, in the county and State of New York, have invented a new and Improved Lock, of which the following is a full, clear, and exact description.

This invention relates to door locks and 10 is an improvement upon a prior invention of a similar nature covered by Letters Patent of the United States No. 1415503, issued on May 9, 1922.

The present invention has to do particularly 15 with the construction of the lock casting and keeper and aims as one of its principal objects to provide a lock in which the bolt is effectively protected against "jimmying" or tampering with either from the outside or inside of the door, both by the keeper and the casing.

The invention aims as a further object 20 to provide a lock keeper and casing construction which is applicable either to a spring lock or locks of the dead-latch type.

With the above recited and other objects in view, the invention resides in the novel construction set forth in the following specification, particularly pointed out in the ap-

30 pended claims and illustrated in the accompanying drawing, it being understood that the right is reserved to embodiments other than those actually illustrated herein to the full extent indicated by the general meaning 35 of the terms in which the claims are expressed.

In the drawing—

Figure 1 is a perspective view of a lock 40 constructed in accordance with the invention illustrating the bolt and keeper in engaged position.

Fig. 2 is an end view of the same with the bolt and keeper in disengaged position.

Fig. 3 is a fragmentary horizontal sec- 45 tional view through the lock and keeper.

Fig. 4 is a rear view of the casing illustrating the keeper in section and engaged with the bolt.

Referring to the drawing by characters 50 of reference, 10 designates the body of the casing and 11 the cover plate therefor, the bolt 12 being slidably mounted in the casing and extending from one end thereof.

As set forth in the previous patent, the 55 bolt 12 embodies an oblong rectangular

skeleton member consisting of side bars 13 and 14 connected at their forward ends by a crossbar 15 extending beyond the side bars as at 16 and 17 and being of substantially triangular shape in cross section to form a sharp web adapted to engage with the keeper. The keeper consists of an angle plate having flanges 18 and 19 adapted to be secured by screws or other fastening devices to the door frame provided with a plurality of spaced rearwardly turned hook members 20, 21 and 22. The hook members are adapted to be normally engaged by the bar 15 of the bolt so that the extensions 16 and 17 of the bar 15 rest against the inner shoulders of the members 20 and 22, while the wedge shaped shoulders 23 and 24 of the casing rest against the outer faces of the members 20 and 22 and the lugs 25 on the outer members 20 and 22 engage suitable recesses 26 in the shoulders 23 and 24.

Any suitable bolt actuating mechanism such as disclosed in the previous patent is arranged within the casing for the purpose of effecting the engagement of the bolt with the keeper by the retraction of the same in the casing and the disengagement of the bolt from the keeper by the projection of the same from its casing.

The means for protecting the bolt when in locked condition, against tampering with or jimmying, and which means constitutes the invention consists in providing the covering plate 11 of the casing with an upstanding rib A at the forward end of said cover plate and forming the cover plate with forwardly projecting guard lugs B, which lugs overlie and cover the side bars 13 and 14 to preclude the possibility of engaging a jimmy or other tool therewith when the bolt is locked. The rib A also acts as a guard for preventing the insertion of a tool between the keeper and the lock and further serves as a strengthening rib. The means for protecting the bolt further includes the formation of guard lugs C on the forward end of the face of the casing body, which lugs overlie and cover the side bars 13 and 14 at the inner side of the lock to preclude and prevent any possibility of engaging a jimmy or other tool with the bolt when locked. As illustrated the connecting web 27 at the juncture of the members 20, 21 and 22 with the flange 19 is rabbeted as at D to receive and accommodate the guard

lugs when the keeper and bolt are engaged.

From the foregoing it will be seen that the bolt in a lock of the character set forth is effectively protected against tampering 5 with or jimmying, and this without material adding to the cost of production.

I claim:

1. The combination with a lock of the character described including a casing, a 10 bolt consisting of a pair of side bars and a crossbar uniting said side bars at the front ends, and a keeper with which the bolt is engageable, of guard lugs extending from one end of the casing and overlying the side 15 bars of the keeper at the front and rear faces thereof.

2. The combination with a lock of the character described including a casing, of a bolt therein composed of a pair of side bars, 20 a crossbar uniting said side bars at their front ends, and a keeper engageable with said bolt, of spaced guard lugs overlying the front and rear faces of the side bars and projecting from one end of the casing, 25 certain of said guard lugs extending into and received by the keeper.

3. The combination with a lock of the character described comprising a casing, a bolt therein composed of a pair of side bars, 30 a crossbar uniting said side bars at their front ends, projections on said crossbars adapted to normally engage a keeper, said

keeper composed of three members, two of which being provided with shoulders for the engagement by said projections of the 35 crossbar, shoulders on said casing engaging the outer faces of the outer keeper members, one of said side bars of the bolt being recessed at its lower edge, of guard lugs formed on and projecting from one end of 40 the casing to overlie and cover the front and rear faces of the side bars, as and for the purpose specified.

4. The combination with a lock of the character described comprising a casing, a 45 bolt therein composed of a pair of side bars, a crossbar uniting said side bars at their front ends, projections on said crossbars adapted to normally engage a keeper, said keeper composed of three members, two of 50 which being provided with shoulders for the engagement by said projections of the crossbar, shoulders on said casing engaging the outer faces of the outer keeper members, one of said side bars of the bolt being recessed at its lower edge, of guard lugs formed on and projecting from one end of 55 the casing to overlie and cover the front and rear faces of the side bars, and outwardly projecting ribs formed at the front and rear 60 of the casing, as and for the purpose specified.

ANDREW YUROW.
